UNITED STATES PATENT OFFICE

2,341,100

ELEVATED STEEL TANK

George T. Horton, Chicago, Ill., assignor to Chicago Bridge & Iron Company, Chicago, Ill., a corporation of Illinois

Application November 4, 1942, Serial No. 464,456

2 Claims. (Cl. 220—1)

This invention relates to improvements in elevated steel tanks and method of erecting the same. My invention is particularly applicable in connection with tanks of the general type shown in my United States Patent No. 2,264,668, granted December 2, 1941, and more especially tanks with horizontal radial legs similar to those shown in Figures 4, 5 and 6 of said patent.

Among the features of my invention is the provision of a substantially spherical tank supported on a substantially cylindrical riser pipe having at the bottom one or more horizontal radial legs with pivot or bearing supports at the ends.

Another feature of my invention is the provision of an improved method of erecting a tank of the character described.

Other features and advantages of my invention will appear more fully as I proceed with my specification.

In those forms of devices embodying the features of my invention, shown in the accompanying drawings, Fig. 1 is a view in side elevation; Fig. 2 is a view taken as indicated by the line 2 of Fig. 1; Fig. 3 is a view showing the tank completely fabricated but before erection; Fig. 4 is a fragmentary view in side elevation showing a modified form; and Fig. 5 is a view taken as indicated by the line 5 of Fig. 4.

As shown in the drawings, the tank includes a substantially spherical portion 10 supported on a substantially cylindrical, but slightly tapered, riser pipe 11 by means of an inverted frustoconical collar portion 12 which joins the spherical portion tangentially.

Structures of this kind are ordinarily built of sheet metal plates of various shapes or sizes suitably welded or bolted together, and no attempt has been made to show the separate plates or their junction lines.

At the bottom of the riser pipe 11 are three radial tapered tubular legs. Two of these legs 15, 15 are diametrically opposed, and the third leg 16 is at right angles to the first two. All the legs are in the same horizontal plane. In describing the tank and in speaking of the riser pipe as being vertical, and the legs 15 and 16 as lying in a horizontal plane, I refer to the position these parts will be in after the tank is erected. As will be explained hereinafter, the tank is fabricated substantially completely with the main body portion 10 resting on the ground and the riser pipe horizontal. After fabrication, the structure is erected by the method hereinafter described.

The outer ends of the legs 15, 15 are pivotally supported in bearings 17 mounted on the founda-

tions 18. The outer end of the leg 16 carries a plate 19 adapted to rest on the concrete foundation 20 when the tank is erected. 21, 21 indicate anchor bolts to hold the plate 19 in position on the support 20.

As mentioned above, the structure is substantially completely fabricated in the position shown in Figure 3 with the body portion 10 resting on the ground 22 and the outer ends of the legs 15 in the bearings 17. When in this position the leg 16 extends substantially vertically upwards. To erect the tank, a cable 23 is attached to the upper end of the leg 16 and pulled by any winch or other source of power (not shown) to raise the tank to the final vertical position. Other means (not shown) may be employed to assist, for example, a derrick or A-frame may be employed to attach a lifting rope to the upper or outer end of the riser pipe 11 to assist in the lifting, especially at the start. Suitable back stays (not shown) are preferably employed to steady the structure and prevent it from going too far as it reaches its final position.

As explained above, the structure is rotated in the pivots 17, 17 until the riser pipe is upright and the plate 19 on the leg 16 rests on the foundation 20. The tank is then in its final erected position. The bearings 11, 17 on the supports 18, 18 and the support 20 may constitute the sole permanent supporting means for the structure, or an additional support such as the concrete pier 24 may also be placed under the bottom of the spherical portion 25 at the lower end of the riser pipe 11, said spherical portion serving to connect the inner ends of the legs 15 and 16 to the riser 11.

The leg 16 may be hollow and communicate with the interior of the riser 11 and may also carry the pipe connection 26 adapted to be connected to the fill and drain pipe 27.

In Figs. 4 and 5 I have shown a modified form of the construction in which only two legs at the bottom are employed instead of three. As here shown, the riser 111 corresponds to the riser 11, and the leg 115 corresponds to one of the legs 15. The opposite leg, however, is omitted and in its place is substituted a trunnion 115a supported in the bearing 117a mounted on the foundation 118a which is also extended to form a support 124 for the spherical portion 125 at the bottom of the riser 111.

The outer end of the leg 115 is mounted in a bearing 117 on the post 118 corresponding to

the bearing 17 and post 18 described in connection with the other form.

Likewise, the leg 116 corresponds to the leg 16 and carries a plate 119 adapted to rest on the support 120 when the tank is erected.

In the form of Figs. 4 and 5 the tank also is fabricated on the ground with the riser 111 substantially horizontal and the leg 116 substantially vertical. The end of this leg is then attached to a suitable cable, such as the cable 23, and pulled downwardly causing the trunnion leg 115 and the trunnion 115a to rotate in their bearings and bring the riser 111 to an upright position until the plate 119 is supported on the post 120. Either of the legs 115 or 116 may be hollow and communicate with the riser pipe and serve for pipe connections as described in connection with the other form.

It will be seen that broadly speaking the invention comprises a tank structure with a riser pipe having a body portion at the top and oppositely extending trunnions at the bottom mounted in bearing supports. In the device of Figs. 1-3 the legs 15, 15, and especially the ends thereof, constitute the trunnions mounted in the bearing supports 17. In the device of Figs. 4 and 5 the leg 115, or the end thereof, is the trunnion, and the opposite extending trunnion is the short shaft 115a mounted in the bearing support 117a.

The foregoing detailed description has been

given for clearness of understanding only, and no unnecessary limitations should be understood therefrom.

What I claim as new, and desire to secure by Letters Patent, is:

1. A storage tank, including: a riser pipe, a body portion supported thereon, a hollow substantially spherical portion at the lower end of the riser pipe and in communication therewith, and oppositely horizontally extending aligned hollow tapering members with their larger ends attached to said spherical portion and serving as supporting legs for the tank, said tapering members acting as trunnions for said tank, and having their smaller ends rotatably mounted in bearings.

2. A storage tank, including: a riser pipe, a body portion supported thereon, a hollow substantially spherical portion at the lower end of the riser pipe and in communication therewith, a horizontally extending hollow tapering member at right angles to the riser pipe and having its larger end attached to said spherical portion, a leg member connected to said spherical portion and extending oppositely from said tapering member, said leg portion and said tapering member serving as supporting legs for the tank and as trunnions for said tank, and said leg portion and tapering member having their outer ends rotatably mounted in bearings.

GEORGE T. HORTON.
